MAGNIFYING LENS FOR ATTACHMENT TO INCANDESCENT ELECTRIC BULBS

Herbert G. Lehmann, Bridgeport, Conn.

Application November 10, 1948, Serial No. 149,572

Term of patent 14 years

(Cl. D57—1)

To all whom it may concern:

Be it known that I, Herbert G. Lehmann, a citizen of the United States, residing at Bridgeport, in the county of Fairfield and State of Connecticut, have invented a new, original, and ornamental Design for Magnifying Lens for Attachment to Incandescent Electric Bulbs, of which the following is a specification, reference being had to the accompanying drawing, forming part thereof.

In the drawing:

Figure 1 is a front view of a magnifying lens for attachment to incandescent electric bulbs, showing my new design.

Fig. 2 is a side view of the lens.

Fig. 3 is a back view of the lens, and

Fig. 4 is an end view of the lens.

I claim:

The ornamental design for a magnifying lens for attachment to incandescent electric bulbs, as shown.

HERBERT G. LEHMANN.
